UNITED STATES PATENT OFFICE

HALBERT B. HALVORSEN, OF MICHIGAN CITY, INDIANA, ASSIGNOR TO SULLIVAN MACHINERY COMPANY, A CORPORATION OF MASSACHUSETTS

AIR-LIFT PUMP

Application filed September 28, 1926. Serial No. 138,297.

My invention relates to air lift pumps, and more particularly to foot pieces for such pumps.

One object of the invention is to provide an improved foot piece—one which shall offer an unobstructed passage to the material to be handled, which shall be comparatively small in proportion to its pumping capacity, which shall be inexpensive and capable of construction of any material of acid-resisting character, and which readily adapts itself to backblowing and cleaning. Other objects and advantages of the invention will subsequently appear.

In the accompanying drawings, in which for purposes of illustration I have shown two forms which the invention may assume in practice,

Fig. 1 is a central vertical section through one form of my improved foot piece.

Fig. 2 is a plan view taken on the section line 2—2 of Fig. 1.

Fig. 3 is a vertical section on the line 3—3 of Fig. 2.

Fig. 4 is a central vertical section through another form of my invention.

Fig. 5 is a vertical section on the line 5—5 of Fig. 6, and

Fig. 6 is a plan view taken on the section line 6—6 of Fig. 4.

Referring to the drawings and first to the illustrative form of the invention disclosed in Figs. 1 to 3, the foot piece is indicated generally at 1. The foot piece 1 may be formed of any suitable material, and being well adapted for handling acids may well be formed of any acid resisting material. It is, in the embodiment in question, formed of two parts: a casing 2 and an aerating section 3.

The casing 2 provides a chamber 4 having spaced upwardly extending portions 5 and 6, separated by a wall 7 and opening into each other at 8 at the bottom of the casing. The bottom of the casing is curved at 9 to promote smoothness of flow and the top of the casing has an integral cover 10 having an opening 11 for the connection of the liquid supply line 12 and an opening 13 for the insertion and mounting of the aerating section 3.

The chamber portion 6 is substantially

larger in cross section than the portion 5 and has a laterally projecting pocket 14 for the aerating fluid connection. The outside wall of the pocket is so formed that its extreme distance from the central vertical line of the foot piece is equal to or less than the distance from said line to the furthest other points in the casing 2. The aerating section 3 comprises a downwardly projecting portion 15 flaring at its lower end, a flange 16 seating on the cover 10, through the opening 13 in which the portion 15 extends downwardly, and an upwardly extending section 18 to which the riser or discharge pipe 19 connects.

The portion 15 has a number of orifices 20 for admitting air or other gaseous pumping fluid, and curves laterally at its lower end towards the chamber 5, terminating just short of the opening 8 so that an annular opening 21 is provided through which sediment may pass into the bottom of the casing. An air or other gaseous fluid pressure line 22 connects with the pocket 14 and so with the space in chamber 6 surrounding the portion 15 of section 3. A clean out plug 23 is removably secured in the bottom of the casing 2. The internal diameter of the section 3 is substantially the same as the internal diameter of the discharge line 19 so that utmost smoothness of flow is obtained. The axes of the connections 12, 19 and 22 are substantially at the edges of a right triangular prism and the parts are so proportioned that when disposed in a casing, one of a minimum size may be used.

The mode of operation of the structure described will be obvious. The foot piece 1 will be disposed in a pit at a suitable depth below the source of liquid to provide an adequate head and connected by the line 12 with such source, while the line 19 leads to the desired point of discharge. The gaseous pumping fluid will be admitted through the pipe 22 and from chamber 6 will pass through the orifices 20 into the section 3 and aerate the column and so effect pumping. The chamber 6 cannot become clogged due to the presence of the annular opening 21 and this is also useful during backblowing. The removal of plug 23 allows removal of sediment.

In the illustrative embodiment of Figs. 4 to 6, the construction is generally similar, but the wall 7' is therein formed by portions which are respectively vertical and horizontal, the latter wall portions provided with the opening 8'. The aerating section 3' is also shorter and unbent throughout its length and the annular opening 21' has its axis substantially vertical. It functions, however, much like the first embodiment described and possesses like advantages.

It will be evident that in each illustrative form I have disclosed a pump which offers a non-obstructed passage to the material to be handled, which is very compact and inexpensive, which readily adapts itself to back-blowing and cleaning and which due to its simplicity lends itself to manufacture of any suitable acid-resistant material.

While I have in this application specifically described two forms and a modification thereof which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a foot piece or pump, a casing member providing substantially parallel upwardly extending chambers connected at their lower ends, one of said chambers having a connection at its upper end for a liquid supply line, a perforated tubular element supported upon the top of said casing member and extending downwardly into said other chamber, an air connection to said last chamber, and a discharge connection communicating with said perforated tubular element, the liquid aerated within said tubular member passing therefrom by way of said discharge connection.

2. In a foot piece or pump, a casing member providing substantially parallel upwardly extending chambers connected at their lower ends, one of said chambers having a connection at its upper end for a liquid supply line, a perforated tubular element extending downwardly into said other chamber, and into adjacency to the point of junction between said chambers whereby an annular opening is provided, an air connection to said last chamber, and a discharge connection communicating with said perforated tubular element, the liquid aerated within said tubular member passing therefrom by way of said discharge connection.

3. In a foot piece or pump, a casing member providing substantially parallel upwardly extending chambers connected at their lower ends, one of said chambers having a connection at its upper end for a liquid supply line, a perforated tubular element

supported upon the top of said casing member and extending downwardly into said other chamber, an air connection to said last chamber opening laterally thereinto, and a discharge connection communicating with said perforated tubular element, the liquid aerated within said tubular member passing therefrom by way of said discharge connection.

4. In a foot piece or pump, a casing member providing substantially parallel upwardly extending chambers connected at their lower ends, one of said chambers having a connection at its upper end for a liquid supply line, a perforated tubular element extending downwardly into said other chamber, and into adjacency to the point of junction between said chambers whereby an annular opening is provided, an air connection to said last chamber opening laterally thereinto, and a discharge connection communicating with said perforated tubular element, the liquid aerated within said tubular member passing therefrom by way of said discharge connection.

5. In a foot piece or pump, a casing member providing substantially parallel upwardly extending chambers connected at their lower ends, one of said chambers having a connection at its upper end for a liquid supply line, a perforated tubular element extending into said other chamber, an air connection directly to said last chamber, and a discharge connection communicating with said perforated tubular element, the liquid aerated within said tubular element passing therefrom by way of said discharge connection, the axes of said connections lying at the edges of a triangular prism.

6. In a foot piece or pump, a casing member providing substantially parallel upwardly extending chambers connected at their lower ends, one of said chambers having a connection at its upper end for a liquid supply line, a perforated tubular element extending into said other chamber, an air connection directly to said last chamber, and a discharge connection communicating with said perforated tubular element, the liquid aerated within said tubular element passing therefrom by way of said discharge connection, the axes of said connection lying at the edges of a right triangular prism.

7. In a foot piece or pump, a casing member providing substantially parallel upwardly extending chambers connected at their lower ends, one of said chambers having a connection at its upper end for a liquid supply line, a perforated tubular element extending into said other chamber and through which liquid normally flows during pumping, an air connection to said last chamber and from which air passes into said perforated element through the perforations thereof, and a discharge connection communicating

with said perforated tubular element, the liquid aerated within said tubular element passing therefrom by way of said discharge connection, the axes of said connections lying at the edges of a triangular prism and the several connections entering said casing in such relation to the central axis of the latter that the outermost point of said air connection is not more remote from said axis than other points in said casing.

8. In a foot piece or pump, a casing member providing substantially parallel upwardly extending chambers connected at their lower ends, one of said chambers having a connection at its upper end for a liquid supply line, a perforated tubular element extending into said other chamber, an air connection to said last chamber and from which air flows to said element through the perforations thereof, and a discharge connection communicating with said perforated tubular element, the liquid aerated within said tubular element passing therefrom by way of said discharge connection, the axes of said connections lying at the edges of a right triangular prism and the several connections entering said casing in such relation to the central axis of the latter that the outermost point of said air connection is not more remote from said axis than other points in said casing.

9. In an air lift pump, a foot piece comprising a casing and a perforated aerating section within said casing cooperating to form an annular air chamber from which air under pressure may be supplied to a rising column of liquid, said aerating section being supported on said casing and depending within the latter and having its lower end cooperating with said casing to form a generally annular opening for the escape of solid material, said opening also serving as an auxiliary aerating means when air is supplied to said chamber in excess of the discharge capacity of the aerating section and said aerating section having the inner wall thereof forming a passageway for the rising column of liquid, and means for supplying air to said annular air chamber at a locus above said annular opening.

10. In an air lift pump, a foot piece comprising a casing and a perforated aerating section in said casing, said casing and section having an annular opening therebetween through which communication exists between the interior of said perforated aerating section and the space between said casing and said aerating section, and means for supplying air to said section at a locus above said annular opening for pumping liquid through said foot piece.

11. In an air lift pump, a foot piece comprising a casing and a perforated aerating section associated therewith, means for supplying air under pressure to said casing for admission through the perforations in said

aerating section, and means whereby air supply in excess of the discharge capacity of the perforations in said aerating section may be discharged to the rising column of liquid including a supplemental passageway of relatively large capacity below the normally operative perforations in said aerating section and below the point of supply of pumping air to said casing.

In testimony whereof I affix my signature. 75
